UNITED STATES PATENT OFFICE.

RUPERT L. GREENLEAF, OF CAMBRIDGE, MASSACHUSETTS.

HEEL-SCOURING MACHINE.

1,351,290.

Specification of Letters Patent. Patented Aug. 31, 1920.

Application filed June 17, 1918. Serial No. 240,405.

To all whom it may concern:

Be it known that I, RUPERT L. GREENLEAF, a citizen of the United States, residing at Cambridge, in the county of Somerset 5 and State of Massachusetts, have invented certain new and useful Improvements in Heel-Scouring Machines, of which the following is a specification.

My invention relates to machines for scouring the breasts of shoe heels and its object is to provide a simple and easily operated machine by which all heels will be scoured alike, no feather edge will be left on the heel, and the operator may finish the 10 heel without moving from his position. Such a machine is illustrated in the accompanying drawings and will be hereinafter fully described, the invention residing in certain novel features which will be particularly pointed out in the claims.

In the drawings,

Figure 1 is a side elevation of a machine embodying the invention;

Fig. 2 is a plan view with parts in horizontal section;

Fig. 3 is a front elevation, the form plates being removed;

Fig. 4 is a detail perspective view of a form plate and the plates by which the 30 abrading members are secured thereto.

In carrying out the invention, I employ a substantial frame or standard 1 having its upper portion bifurcated, as shown at 2, and provided with bearings 3 for a driving 35 shaft 4. Fast and loose pulleys 5 and 6 are fitted on the driving shaft between the bearings 3 and on the front of said shaft is a crank disk 7. On the front side of the frame are projections 8 constituting guides for a 40 reciprocating carrier rod 9, and a link or pitman 10 has one end pivoted to said rod and its opposite end pivoted eccentrically to the crank disk, as shown most clearly in Fig. 1.

Secured to and projecting forwardly from the carrier rod 9, are supporting arms 11 having their front ends offset, as at 12, whereby the polishing or scouring instrumentality will be properly disposed for 45 convenient and successful operation. The scouring or polishing tool comprises a form plate

13, a cushioning cover or pad 14, abrading members 15, and clamping plates 16. The 50 form plate is a rectangular metal blank curved or otherwise shaped transversely, as indicated at 17, so that it will conform to

the shape of the heel breast, it being the intention to provide a plurality of form plates which may be used interchangeably. The form plate is covered with felt or other 60 yieldable material to provide the cushion or pad 14 and the abrading members 15, which are preferably strips of emery paper, are drawn smooth over the pad. The clamping plates or strips 16 of metal or other rigid 65 material are placed over the edges of the abrading members against the back of the form plate and secured in place by screws or bolts 18 and 19, the screws 19 also securing the device to the offset ends 12 of the 70 supporting arms 11. The upper abrading member is finer than the lower member.

Below the scouring tool, a funnel 20 is provided, said funnel leading to a suction device so that the dust arising from the 75 operation of the machine will be carried off in a well-known manner.

The operation of the machine will be readily understood. The operator stands in front of the machine and holds the shoe 80 against the scouring tool as indicated in Fig. 2 and the tool reciprocates vertically across the breast of the heel, producing a smooth surface thereon. The operator merely holds the heel against the tool and 85 to finish the heel simply lifts it to the higher abrading member.

In scouring machines now generally used, the work is done by wheels which travel 90 constantly in one direction, and consequently, form a feather edge or bur on one side so that the heel must be reversed and applied to a second wheel before it is finished. In my machine, the tool moves in both directions across the heel and no bur 95 is formed, the operator being enabled to finish the heel without leaving his position. It is not necessary to mold the abrading cloth as it may be cut in lengths from the supply roll and placed directly against the pad. 100 The form plates will have the same curve as that originally given the heel and may be easily and quickly interchanged.

Having thus described my invention, what is claimed as new is:

1. Means for securing the breasts of shoe heels comprising supporting arms carrying a form plate of curved cross section and of approximately uniform thickness throughout its extent, a yieldable cover over the 110 front face of the form plate, an abrading strip fitting over the cover with its longi-

- tudinal edges against the back of the form plate, clamping plates fitted against the abrading strip at the back of the form plate and extending longitudinally of the form plate, means for securing one clamping plate and the adjacent side edges of the cover and of the abrading strip to the form plate, and means for securing the other clamping plate and the adjacent side edge of the cover and of the abrading strip to the form plate and to the ends of the supporting arms, the first-mentioned clamping plate and the parts held thereby being entirely free of the supporting arms.
- 15 2. Means for scouring the breasts of shoe heels comprising a relatively thin metallic plate having its outer face straight in longi-

tudinal dimension and conforming in its transverse dimension to the configuration of the breast of the heel, a cushion covering 20 said plate, an abrading strip covering the cushion and having its longitudinal side edges carried around the edges of the form plate and against the back of the same, a support, and means for securing the side 25 edges of the abrading strip to the back of the form plate, and one of said side edge securing means also securing the form plate adjacent one side edge to the support, the opposite side edge of the form plate being 30 free.

In testimony whereof I affix my signature.

RUPERT L. GREENLEAF. ;[L.S.]
